DESIGN FOR A SHOE

Henriette Simon, New York, N. Y.

Application October 15, 1941, Serial No. 193,777

Term of patent 3½ years

To all whom it may concern:

Be it known that I, Henriette Simon, a citizen of the United States of America, residing in the city of New York, county of New York, and State of New York, have invented a new, original, and ornamental Design for a Shoe, of which the following is a specification, reference being had to the accompanying drawing, forming part thereof.

The figure on the drawing is a perspective view of a shoe showing my new design. The opposite side presenting substantially the same appearance as the side shown.

My design comprises of a triple saddle on the vamp portion of the shoe, the center portion of which flaps back and is attached to the top side of the insole; the other two adjoining portions of the saddle are attached between the under side of the insole and the upper side of the bottom sole.

I claim:

The ornamental design for a shoe, substantially as shown and described.

HENRIETTE SIMON.
